UNITED STATES PATENT OFFICE.

JOHN BAUDER, OF CINCINNATI, OHIO.

TOY VEHICLE.

Application filed August 9, 1921. Serial No. 490,994.

To all whom it may concern:

Be it known that I, JOHN BAUDER, a citizen of the United States, residing at the city of Cincinnati, in the county of Hamilton and State of Ohio, have invented certain new and useful Improvements in Toy Vehicles, of which the following is a specification.

The object of my invention is to produce a toy vehicle, simple in construction, cheap of manufacture, highly efficient in use and which shall possess a marked degree of utility in this class of toys. It is "knock-down" in construction for shipping purposes and can be readily assembled; this "knock-down" feature also enables me to pack the same in boxes, preventing these toy vehicles from becoming shop worn and I can ship them at a lower rate and handle same more conveniently. Other features consist in hinging the bolster which carries the rear wheels, to the seat body, so that said parts will swing, and in forming a foot rest or rests at the lower part of the steering rod 25 above the front wheel or wheels, which can also be used as a brake by the operator. It consists of two "knock-down" sections, which when set up form the vehicle.

In the accompanying drawing forming part of this specification:

Fig. 1, is a plan view, looking down upon the toy vehicle,

Fig. 2, is a side elevation of the vehicle shown in Fig. 1, partly broken away to show construction,

Fig. 3, is a side view in elevation of the entire vehicle in a "knock-down" condition,

Fig. 4, is a plan view of the parts shown in Fig. 3 as they appear in "knock-down" form,

Fig. 5, is a side view in elevation of all the parts in "knock-down" form, except the steering rod and front wheels,

Fig. 6, is a view in elevation of the upper part of the steering rod, looking at the same from the side,

Fig. 7, is a view in elevation of the lower part of the steering rod and front wheels, looking at the same from the side, and Fig.

50 8, is a section on line 8—8 of Fig. 2, partly broken away, the axle shown in full lines.

The supporting body or member upon which the child sits in operating the vehicle, in the present instance, is composed 55 of a seat part 1, and head part 2, and a

neck part 3, generally made integral and of any desired contour, and as a unit may be designated as a seat board.

At the rear of the seat part 1, I place a transverse bolster 4, and I preferably hinge 60 or movably connect it to the bottom of said seat part 1, so that it will swing, the hinge for holding it to the seat part, being marked 5. The upper end of the bolster in its set position engages into a transverse notch 10 65 formed in the lower side of the seat board for stabilizing the bolster. To the lower extremity of this bolster, I connect the rear wheels 6, by a shaft or axle 7, which extends entirely through the bolster. The bottom 70 of the bolster is recessed as shown at 8, and in this recessed part one end of a brace rod 9 is held in position by the shaft or axle 7 passing therethru; thus enabling said brace rod to swing on said axle 7, when the vehicle 75 is in a "knock-down" form; I may connect the bolster and wheels and the rod in any other practical way, if I desire to do so.

At the forward part of the supporting body, underneath the same, I connect a brace 80 block 12, having a forked end 13; in this forked end the forward end of the brace rod 9 fits and is held in position by a removable pin 14; I may loosely connect it in some other way if desired.

A steering post, of sectional form is engaged through the front head part 2 of the supporting body and through the front end of the brace block 12, formed of an upper section 15 and a lower section 16, the upper 90 section provided with a stem or rounded pin shaped end 17 engaged into an elongated recess 18 in the upper part of the lower section 16, and is rigidly held in position therein by screw 19. Washers, as 20¹ usually being employed on the steering rod to make a better bearing surface at the point where the steering rod passes through the supporting body and brace block. The two sections are united to pivot the shouldered end, at the 100 formation of the stem 17 of the upper section into swivel engagement with the upper side of the seat board, and the end of the lower section into bearing engagement with the lower face of the brace block, as a rigid 105 part of the seat board, and with intermediate portion of the stem 17 of the upper section swiveled or joined in the seat board, adapting the steering part to be revolved for steering the vehicle.

At the upper extremity of the steering rod or post I place a handle 20, which passes therethru and is so fitted therein that the same is revolvable. This permits the user to 5 grip the handle tightly and satisfactorily with his hands, affording wrist movement for exercising functions. At the lower extremity of said steering rod or post at opposite sides thereof I place the front wheels 10 21, which are held on a short shaft or axle 22 passing through said steering rod; one wheel may be used if desired and connected in any desired manner.

To the steering rod, just above the front 15 wheels I pivotally connect by a pin 23, two foot supports or rests 24, one on each side of said steering rod or post serving also as braking means for the wheels. I may use only one of these foot rests or supports. By 20 allowing the heel to extend over the back edge of said foot rest parts, the operator can use the heel to act as a brake for the wheel or wheels. I may connect and shape this foot rest in any way found desirable in 25 practice.

Referring to the "knock-down" feature of this toy vehicle; on account of the bolster being hinged to the seat body thus rendering it capable of swinging and carrying the 30 wheels with it, and by reason of the brace rod being pivoted to swing on the bolster, the seat part and the brace block, the bolster and rear wheels and brace rod can be folded together into a position shown in Figure 5. 35 The steering rod or post, carrying the handle, front wheels and foot supports can be separated through medium of screw 19 and can be associated with the parts shown in Fig. 5, so that the whole vehicle will appear 40 in a "knock-down" form as shown in Fig. 3. It will be readily apparent that the parts as assembled and shown in Fig. 3 can be placed into a box and shipped.

To set up the vehicle all that is necessary 45 is to swing the bolster backward into the position it normally occupies, and swing the brace rod 9 into the forked end of the brace rod 12 and insert the pin 14, then connect the top and bottom sections 15 and 16 of the 50 steering rod through the front end 3 of the seat part and through brace block 12, and insert the screw 19; this can be done quickly and forms a strong and serviceable toy vehicle. To the back of the bolster I usually 55 connect a spare wheel 25 as shown.

I wish to be understood as claiming any modifications of this toy vehicle which fall

within the scope of this specification and claims.

What I claim as new and my invention 60 and desire to secure by Letters Patent is:

1. A wheeled toy comprising a platform on which the operator may sit and propel the toy, a rear axle for the platform provided with supporting wheels, a steering 65 post connected to said platform and adapted to support the front end of the same, steering wheels supporting said post, and foot-support-means pivotally mounted on said post and cooperating with the steering 70 wheels to form a brake.

2. A wheeled toy comprising a platform, a rear bolster connected to the underside thereof and provided at the center of its lower edge with a slot, an elongated member secured upon the underside of the platform and formed at its rear portion with a U-shaped socket, a brace bar having one end detachably connected within said socket and having its other end disposed within said 80 slot, a rear axle passing through the lower portion of said bolster and through the second-named end of said brace bar, rear wheels on said axle, a steering head having a reduced extension revolvable through 85 steering holes in the forward end of the platform and the forward end of said elongated member, and a member carrying front wheels and having a recess within which said extension is detachably engaged. 90

3. A toy vehicle as claimed in claim 2 in which foot-support boards are pivotally mounted on the last mentioned member and cooperate with the front wheels to form a 95 brake.

4. A toy vehicle of the class described, a seat board, a rear wheel carrying bolster hingedly connected to and having a mortised engagement with said seat board, a brace member connecting said seat board and bolster and separable therefrom, for swinging the bolster to a "knock-down" position, a wheel carrying steering post swiveled on said seat board, having a pair of ground wheels journaled thereon, respectively at 105 opposite sides thereof, and foot supports pivotally mounted on opposite sides of said post, adapted to be brought into braking engagement with said wheels. 100

In testimony whereof, I affix my signature 110 at Cincinnati, Ohio, this 16th day of June, 1921.

JOHN BAUDER.
